(57) **CLAIM**

The ornamental design for a planter, as shown and described.

DESCRIPTION

FIG. 1 is a top, left side perspective view of the planter;

FIG. 2 is a front elevational view thereof;

FIG. 3 is back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line portions are shown for environmental purposes and form no part of the claimed design.
